SET OF CHESSMEN

Ernest N. Wright, Belmont, Mass.

Application March 9, 1953, Serial No. 23,943

Term of patent 7 years

(Cl. D34—5)

To all whom it may concern:

Be it known that I, Ernest N. Wright, have invented a new, original, and ornamental Design for a Set of Chessmen, of which the following is a specification, reference being had to the accompanying drawing, forming a part hereof.

Figures 1 to 6, inclusive, are isometric views, respectively, of a king, queen, bishop, knight, castle, and pawn in a set of chessmen, showing my new design;

Figure 7 is a side elevation of the knight shown in Figure 4;

Figure 8 is a front elevation of the knight shown in Figure 4;

Figure 9 is a plan view of the castle shown in Figure 5; and

Figure 10 is an elevation of the castle shown in Figure 5 partly in section.

I claim:

The ornamental design for a set of chessmen, as shown.

ERNEST N. WRIGHT.
